UNITED STATES PATENT OFFICE.

HUMPHREY R. WARD, OF CLEVELAND, OHIO.

AEROPLANE.

1,160,020.

Specification of Letters Patent.

Patented Nov. 9, 1915.

Application filed November 12, 1913. Serial No. 800,635.

To all whom it may concern:

Be it known that I, HUMPHREY R. WARD, a citizen of the United States, residing at Cleveland, in the county of Cuyahoga, State of Ohio, have invented certain new and useful Improvements in Aeroplanes; and I do hereby declare the following to be a full, clear, and exact description of the invention, such as will enable others skilled in the art 10 to which it appertains to make and use the same.

This invention relates to aeroplanes. It is well known that in the construction of devices of this character one of the most 15 important, if not the vital point of all, is the insuring of stability in the device so that if, by reason of accident or inadvertence the machine becomes misplaced from its proper position in the air no serious results 20 may take place. This stability may be attained either by automatic stabilizing devices or, as in the present instance, by so arranging the machine itself that it possesses inherent stability. Moreover, in machines of this description such inherent stability depends to a great extent on the precise arrangement and angular relation of the planes, ailerons, rudders and fins and the arrangements at present in use vary 25 greatly in the degree of their stability.

The principal object of the present invention is to provide an aeroplane of improved construction wherein the planes will be so arranged as to effect a superior or inherent stability in the machine. In the production of this result there is provided a novel arrangement and form of main plane which are so devised that whenever the machine tilts laterally to a degree sufficient 30 to produce slight sliding movement sidewise an upward pressure on the lower end and a downward pressure on the upper end of the lower plane will be produced with a resultant restoring of the machine to its 35 proper position in the air. This object is furthermore attained by so arranging a main plane and the elevating plane of a machine that they are both substantially at the same dihedral angle. Still further 40 assistance in the attainment of the objects is obtained by arranging the ends of a main plane, the side of the elevating planes, and the ailerons so that, in the normal position of said ailerons and elevating planes, all of 45 these planes on one side of the machine are

parallel, the planes on the other side of the machine are parallel and all arranged with their side portions at equal dihedral angles.

Another object to be accomplished in this invention is to provide ailerons, so arranged 60 with respect to the main plane of the machine that during banking the lower ailerons will be in a substantially horizontal position so that when manipulated by the operator in resuming straight flight the stabilization 65 will be quickly effected.

It is also well known that the relative position of the propeller and stabilizing devices such as fins and the like exert a great influence on the stability of the machine. 70

A still further object of the present invention is to provide an improved fin arrangement which is so positioned with respect to the propeller, and with respect to the propeller and main planes or plane, that 75 a high degree of stabilization will be effected.

With the above and other objects in view the invention consists in general of certain novel details of construction and combination 80 of parts hereinafter fully described, illustrated in the accompanying drawings, and specifically claimed.

In the accompanying drawings, like characters of reference indicate like parts in 85 the several views, and Figure 1 is a plan view of a biplane embodying this invention. Fig. 2 is a front elevation thereof. Fig. 3 is a side elevation of the device. Fig. 4 is a vertical longitudinal section through 90 the device. Fig. 5 is a detail perspective view of the elevating planes and the manner of mounting the same. Fig. 6 is a front diagrammatic view illustrating the action of the air current on the machine when 95 tilted. Fig. 7 is a diagrammatic view in plan illustrating the action of the air current when the machine shifts from its proper direction. Fig. 8 is a horizontal section on the line 8—8 of Fig. 2. 100

In carrying out the objects of the invention there is provided an upper main plane 10 the lateral portions of which are in alignment and a lower main plane 11 the lateral portions of which are arranged at a dihedral angle with respect to each other. These two planes are, in cross section, of the usual curved stream line contour. In plan the upper plane is rectangular and consists of a frame comprising the cross ribs 12 con- 105

110

nected by the longitudinal bars 13, this frame being covered with a suitable covering element 14 properly attached to the frame so that the required degree of rigidity is attained. The lower plane 11 is, as previously mentioned, of the dihedral type. This plane consists of a skeleton frame composed of the cross ribs 15 and longitudinal bars 16 which support the covering element 17 applied as to the upper plane. The central portion 18 of this plane is arranged parallel to the plane 10 while the ends 19 of the lower plane incline upwardly toward the upper plane and terminate in vertical alinement with the ends of the upper plane. Moreover the angle of the plane ends 19 is such that the tips of these planes lie substantially half way between the plane of the portion 18 of the lower plane and the upper plane. When the planes are in this arrangement and tilting takes place, as illustrated in Fig. 6, the air current which enters between the two planes at the end thereof will be deflected from the upper plane and strike 25 the lower plane on the opposite side beyond the center. There is thus produced an upward pressure on the lower end of the upper plane and a downward pressure on the upper side of the lower plane. When both 30 planes are arranged at the same dihedral angle or when both planes are parallel and straight the air current entering at the lower end of the plane simply flows along the upper plane, when both are straight or when 35 both are at the same dihedral angle this air current is deflected and strikes the lower plane either at the center or at the lower side of said lower plane, thus being ineffective in its deflected portion to restore the machine 40 to even keel.

The upper and lower frames are connected by vertical struts 20 which are suitably braced by stay wires 21. In the present instance the machine is of the headless type 45 and is controlled from the tail carried by the body of the machine and which is supported on a frame comprising outriggers 22 extending from the upper frame rearwardly and connected at their rear ends by a cross 50 bar 23. This frame furthermore includes lower outriggers 24 also connected at their rear end by a cross bar 25, both cross bars being connected by outer vertical bars 26 and a central vertical bar 27. This central 55 vertical bar extends in the plane of the central longitudinal axis of the machine. Connecting the bars 26 with the bar 27 is a pair of rods 30 which are arranged at an angle with respect to each other, said angle corresponding to the dihedral angle of the lower 60 main plane. Secured to these bars 30 by means of eyes 30' are the elevating planes 28 and 29 which are of rhomboidal contour and are thus arranged one on each side of 65 the bar 27 and lie parallel to the lower main

plane when the elevating planes are in their normal or horizontally guiding position and the machine is viewed from in front.

By means of this arrangement the pressure on the tail or elevating plane will be 70 made more nearly equal to the pressure on the lower main plane when the machine is tilted with respect to the variation in pressure on opposite ends of said lower main plane and opposite sides of the tail so that 75 twisting of the operator frame is eliminated.

The elevating planes are controlled by the usual wires 31 and 32 connected to the top and bottom faces of the planes and operatively connected to the pivoted control 80 standard 33 which is rocked in the usual manner by the operator to swing the elevating plane.

The vertical rudder 34 is disposed in advance of the elevating planes, and in neutral position, extends in the plane of the longitudinal axis of the machine as is usual with devices of this description. This vertical rudder is hinged at its forward edge to cross bars 35 which connect the upper and lower outriggers in pairs respectively, and is controlled by the usual wires 36 and 37 operatively connected to the control standards 33. 85

The ailerons are indicated at 38 and 39 95 and are arranged one at each end of the main planes of the machine and normally extend parallel with the related ends of the lower main plane which is arranged at a dihedral angle. The ailerons thus slope toward each other and thus form a dihedral angle similar to the dihedral angle of said plane. These ailerons are located substantially midway between the outer ends of the lower and upper planes and project laterally 100 beyond the plane for a distance about one-third of the width of the ailerons while they project inwardly for a distance about two thirds of their width. In order to hold these ailerons in position on the frame the outer struts 20 are connected by bars 40 at each side of the machine so arranged that the bars are parallel with the front edges of the end portions of the lower main plane. These ailerons are adapted to be moved simultaneously in opposite directions by control wires 41 and 42 which are operatively connected to a swinging frame 43 within which the operator sits and sways to the right or left in the usual manner as the machine 110 moves off an even field and is inclined laterally in one direction or the other. 115

Again referring to Fig. 6 it will be noted that when the machine is in the position indicated in that figure the outer end of the lower of the ailerons receives the impact of the air current as the machine drops side-wise and that this air current is led in between the upper and lower planes and passes upward to strike the upper plane 120 125 130

about half way distant from the extremity of said upper plane to the center of the same. At this point the air current is deflected downward and strikes principally 5 about half way distant from the center to the outer edge of the lower main plane on the upper side of said lower main plane. Moreover the lower aileron 38 and the lower side of the lower main plane are both in a 10 substantially horizontal position so that the falling of the machine exerts a greater force on this side of the machine than on the other side thereof and thus tends automatically to restore the stability, this effect 15 being assisted by the action of the dihedral elevating plane. Moreover, when the aileron at the lower portion of the machine is nearly horizontal the moving of this aileron to raise this lower side by depressing its rear 20 edge, will operate more effectively than where the aileron is inclined, as for instance if it were parallel to the straight upper plane. The reason of this is that the angle of incidence of the rising air and the lower 25 aileron is substantially a right angle, the pressure upward thus being substantially normal to said aileron. In order to assist in this transverse stabilization and also in order to more particularly stabilize the 30 direction of movement of the machine forwardly there is provided a certain fin arrangement. This stabilizing is accomplished by means of a vertical fin 44 which is mounted in upright position in the center of and 35 on the top face of the upper main plane. It is to be noted that the upper main plane extends slightly over the propeller 45 and that the lower main plane is cut away at 40 to accommodate the sweep of the propeller blade in passing through its lower arc of motion. This fin is so arranged that it projects rearwardly of the upper main plane and begins at the forward edge of said upper main plane. In the present showing 45 there has been illustrated a triangular fin which rests on its hypotenuse and has its right angle 46 extending upwardly to form the apex, this right angle being located substantially over the propeller 45 as above noted. When thus arranged it is found that 50 the air currents, during the flight of the machine, when the latter deflects from its forward course strike this fin and pass through a course, substantially that of the arrows indicated in Fig. 7, so that the rudder 34 receives the impact of the current and the 55 machine straightens out on its course. In this connection it is explained that, referring to Fig. 7, the line of motion of the aero- 60 plane is indicated by the arrows to the right and left hand side of the figure. The aeroplane is shown in a position such as it will assume when "skidding", that is, while

moving forwardly in the direction of the arrows referred to it will also be turned 65 about the vertical axis through the middle point of the plane 10 and consequently the current of air which moves parallel but in the reverse direction to the line of movement of the aeroplane strikes against the 70 plane or pin 44 and is consequently deflected as indicated by the arrows but tends to "straighten out" into the line of motion of the aeroplane.

The body of the machine is supported 75 upon the usual running gear 27 and as usual in biplanes the engine 48 is supported in rear of the operator's seat 43 upon a bed frame 49.

From the foregoing it will be obvious 80 that in the machine, thus provided, there is an inherent stability due to the peculiar arrangement of the two main planes, the ailerons, the tail planes or elevating rudders and the fins which greatly assist the operator 85 in maintaining proper control of the machine and which, in the event of the operator losing control of the machine, acts to automatically restore stability of the aeroplane and thus prevent dangerous accidents. 90

Having thus described the invention, what is claimed, as new, is:

1. In a biplane, a straight upper main plane, a lower dihedral main plane, ailerons 95 parallel with related ends of said lower main plane, and rear elevating planes parallel with related ends of said lower main plane.

2. In a biplane, a straight upper main 100 plane, a lower dihedral main plane, ailerons disposed at a dihedral angle to each other similar to the dihedral angle of said lower main plane, and elevating planes disposed at a dihedral angle to each other similar to 105 the dihedral angle of said lower main planes.

3. In a biplane, a flat main top plane, a dihedral main lower plane, ailerons arranged at a dihedral angle to each other in 110 spaced relation to the ends of the lower plane, and elevating planes arranged at a dihedral angle to each other.

4. In a biplane, a flat main upper plane, a dihedral main plane, ailerons arranged at 115 a dihedral angle to each other, and elevating planes arranged at a dihedral angle to each other, all of said dihedral angles being normally equal.

In testimony whereof, I affix my signature, in the presence of two witnesses.

HUMPHREY R. WARD.
